(57) **CLAIM**

The ornamental design for a display module for an electronic device, as shown and described.

DESCRIPTION

FIG. 1 is a perspective view of a display module for an electronic device showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is an enlarged view of a lower portion of FIG. 1. The broken line portions of the display module for an electronic device in FIGS. 1–8 represent unclaimed portions of the design and form no part thereof.
